UNITED STATES PATENT OFFICE

2,469,020

AWNINGS AND MEANS FOR SUS-
PENDING AWNINGS ON SAID HANGERS

Robert D. Thomson, Lynn, Mass.

Application May 21, 1945, Serial No. 594,937

5 Claims. (Cl. 160—77)

1

Heretofore the hanging of awnings has been very troublesome and time consuming. It requires the installation of many cleats on the building which have to be removed if they are in the way of storm windows or shutters or both. The existing methods also require the use of many screw eyes which are troublesome and sometimes wear the awning. These methods also involve the installation and removal of a number of loose parts and the rattling of the same due to loose fits in the ordinary commercial awning hardware. These methods also involve annoyance due to the loss of these loose parts after removal at the end of the season; also the wearing of the window casing due to the fastening and unfastening of fixtures and insertion and withdrawal of screws. In the case of the pulleys at the top they are usually left on the window casing and they become corroded. Their leather strips disintegrate, the ropes become worn and holes are pinched in the awnings. In the case of all buildings on which there are used both awnings in the summer and storm sash in the winter, and which also have shutters, a serious difficulty is experienced in the necessity of unscrewing the side awning fixtures from the building in the fall and removing the pulleys at the top, and then of screwing these parts on the building in the spring. These difficulties, experienced under the pressure of peak seasonal loads are principally responsible for the excessive labor turnover among awning service workers and limit the size to which awning service companies can normally grow.

My invention has for its object to avoid these and other objections by providing a head rod having suitable fixtures for engaging complementary fixtures on the house, piazza or other structure upon which the awning is to be hung.

Another object of my invention is to provide a special head and frame construction for the awning to which the latter is attached which awning may be folded and suspended from the head, thus relieving the cumbersomeness of the awning while engaging the head with the suspending hangers or hooks.

Another object of my invention is to provide novel means for suspending the awning frame from certain fixtures on the window casing or woodwork which will not interfere with the hanging of storm windows, etc.

Another object is to eliminate the necessity for using many loose parts, and to be able to have the pulleys permanently attached to the head rod instead of on the house or other structure

upon which the awning is installed, thus conserving the pulleys and avoiding holes in the window frame.

Still another object of the invention is to materially reduce the cost of hanging and taking down awnings.

The objectives and advantages of my invention will be more clearly understood by referring more specifically to the following specification and to the drawings wherein Fig. 1 is a perspective view of my improved awning in place on a window frame or casing; Fig. 2 is an enlarged view of one end of the head-rod; Fig. 3 is a section through the head-rod taken on line 3—3 of Fig. 1; Fig. 4 is a plan view of one of the side hinged hangers; Fig. 5 is a top view of one of the side hangers and a section through the window casing and illustrating the method of folding said hanger; Fig. 6 is a section through one of the side hangers and illustrating the method of locking one of the awning side frame rods therein; Fig. 7 is a front elevation of the awning initially folded and suspended on the awning head pins, and illustrating the method of springing the frame therefrom (shown in dotted lines); Fig. 8 is a side elevation of Fig. 7; Fig. 9 is a side elevation of the awning suspended from a window casing or other suitable structure, and showing the method of inserting the side rods of the awning frame in the side hanging fixtures or holders, and Fig. 10 is a perspective view of one of the side hangers.

Referring more specifically to the accompanying specification and drawings, 1 represents a novel construction of head-rod which may be of any suitable material such as wood, non-corrosive metal or plastics. To this head-rod 1 the awning 2 is attached, and the shape of the head-rod conforms to the shape of the awning when it hangs in its normal position. Cleats 3 provided with hooks 4 are secured to the window casing 5 by screws 6. To the head-rod 1 are suitably secured by suitable fastening adapters 7 having slots or eyes whereby the head-rod and the awning 2 attached to the top of the latter may be suspended from the hooks 4 on the window casing. The head-rod locks beneath the cleats 3 thus preventing rattle. The longer the awning the more adapters with corresponding cleats are required. Protruding pins 8 extend beyond the ends of the head-rod 1. For ease of manipulation the awning is first suspended or hung on these pins in order to avoid the cumbersomeness of the awning while it is being adjusted to its final hanging as illustrated in Fig. 7, wherein the

frame 9 of the awning is turned inwardly and the ends thereof which are provided with slotted openings 10 (Figs. 8 and 9) are sprung onto the pins 8.

On the window casing 5 are suitably secured to said casing hinged fixtures 11, 11', the latter shown in dotted lines, and the hinges themselves being illustrated at 12. These hinged fixtures are provided each with a bar 13, best illustrated in Fig. 10. This bar may be shaped as desired in any form which will best cooperate with the slotted openings 10 in the ends of the frame pieces 9 in order to lock said frame in the fixtures 11, 11' by turning the frame ends thereon as shown in Fig. 9. The purpose of the hinging of the fixtures is so that they may be folded, and not necessitate removal of the fixtures in order to properly locate them to cooperate with the awning frame 9.

The folding of these hinged fixtures is best illustrated in Fig. 5, wherein fixtures 11 and 11' may be folded back on hinge 12 as shown in dotted lines, thus leaving space on the window casings for storm windows to be hung.

The operation of my invention is as follows:

The cleats 3 provided with the hooks 4 are first screwed or suitably secured to the top of the window casing 5 or other structure upon which the awnings are to be hung. These cleats may be left permanently on the house to serve for hanging storm windows thereon in the fall if desired. The folding or hinged fixtures 11 and 11' are also secured to the window casings or other suitable structure as illustrated in Fig. 1. Before suspending head-rod 1 on the hooks 4 the frame 9 to which the awning is attached is turned inwardly and upwards so that the slotted ends of the frame may be hung on the pins 8 of the head-rod as shown in Figs. 7 and 8. The weight of the awning and frame is now supported from the head rod 1 so that the person hanging the awning can conveniently handle the assembly as a unit. The head rod and assembled parts supported on the pins 8 of the head rod is now hung on the hooks 4 of the cleats 3. The frame 9 is sprung away from the pins 8 as shown in Fig. 7 and turned downwardly so that the slotted ends 10 of frame 9 may embrace flat bars 13 of fixtures 11 and 11', and turned in the direction of the arrow, Fig. 6. The frame 9 is now in a horizontal position as shown in Fig. 1 and in dotted lines, Fig. 6. The awning is now hung in its summer position with the head-rod supported from the hooks on the structure to which the awning is attached, and likewise the awning frame which partly supports the awning is itself supported in the folding fixtures 11 and 11'.

It will be seen that my invention provides a simple and economical means for servicing awnings while eliminating the possible loss or deterioration of loose parts, the rattle of the latter, and the time consumed by the service man enabling him to expand his business field because of the saving of labor for a given amount of servicing done.

My invention may be embodied in many other forms than those shown and described and I therefore do not restrict the appended claims to those forms, but intend to cover all changes and modifications within the spirit and scope of my invention.

What I claim as new and desire to secure by Letters Patent of the United States is:

1. An article of manufacture comprising an awning device having means of support from a

suitable structure such as a window frame and a second means of support comprising a pair of bars horizontally mounted one on each side of said window frame, a head having pins projecting from each end thereof, means such as hook-eyes on said head for engaging said first mentioned supporting means on the window frame, an awning frame comprising members to which an awning is attached, and other members connected to said frame having slotted eye-ends adapted to selectively embrace the projecting pins on the head and the horizontal bars on the window frame.

2. An article of manufacture comprising an awning device adapted to be hung from suitable fixtures on a structure to be shaded by said device, a head provided with laterally projecting terminating pins, one on each end of the head, means on the head for engaging certain of the fixtures on the structure, and a frame comprising members certain of which have connected therewith slotted-eye-ends adapted to selectively engage certain of the fixtures on the structure and the above mentioned terminating pins.

3. In combination with a structure to be shaded, comprising a window frame having thereon hooks and a pair of fixtures, each of the latter supporting a horizontal flat bar therein, and an awning device adapted to be hung from the hooks on the window frame, a head for the device having means such as hook-eyes for engaging the hooks on the window frame, an awning frame attachable to said head, and members having bifurcated ends such as slotted eye-ends connected with the frame, the bifurcated connected members adapted to cooperatively engage the respective horizontal flat bars supported by the pair of fixtures.

4. An awning device having means of support from a window-frame including a pair of hooks and a pair of foldable fixtures each of the latter provided with a hinge pin mounted in the fixture, a head to which the awning is attached carrying cooperating adapters having eyes for engaging the hooks on the window frame and laterally projecting pins, and a frame to which the awning is attached, said frame having slotted eye-ends adapted to embrace selectively the projecting pins on the head and the fixtures.

5. An article of manufacture comprising an awning device having means of support from a window frame including a pair of hooks and a pair of hinged foldable fixtures, each fixture having a horizontal bar mounted therein, a head for said device provided with fixtures forming hook-eyes, an awning and a frame therefor, the latter comprising members to which said awning is attached, and other members connected to said frame having bifurcated ends such as slotted eye-ends adapted to cooperatively embrace the horizontal bars on the window frame fixtures, whereby the awning frame may be raised and lowered while still engaged with the horizontal bars of the fixtures.
